UNITED STATES PATENT OFFICE.

BERNARD MORAHAN, OF NEW YORK, N. Y.

RANGE-BOILER.

SPECIFICATION forming part of Letters Patent No. 250,451, dated December 6, 1881.

Application filed August 17, 1881. (No model.)

To all whom it may concern:

Be it known that I, BERNARD MORAHAN, of New York city, in the county and State of New York, have invented certain new and useful Improvements relating to Range-Boilers, of which the following is a specification.

What I term a "range-boiler" is the commonly-known closed vessel connected by pipes to the kitchen-range for heating water and delivering it, as required, through pipes for use. I make the range-boiler in pretty nearly the ordinary form—a tall upright vessel, circular in horizontal section and with rounded or tapered ends. I mount it on a convenient stand and connect it in the ordinary manner.

15 The material of the boiler is important. Iron is cheap and strong; but its tendency to rust is a serious objection and forbids the use of water therefrom for washing clothes. Copper is expensive when made of sufficient thickness to afford adequate strength and stiffness. I make the boiler of ceramic ware—a strong white ware—the same that I have employed in ceramic wash-tubs, now extensively used in 20 the better class of houses. The material affords great strength and stiffness.

25 The accompanying drawings form a part of this specification, and represent what I consider the best means of carrying out the invention.

30 Figure 1 is a central vertical section through what I esteem the preferable construction. Fig. 2 is a corresponding section representing a modification.

35 Similar letters of reference indicate corresponding parts in both the figures.

There are two classes of strains to which range-boilers are subjected—one the expansive strain due to steam suddenly engendered. This 40 can never become but a little greater than that due to the head of the water in the street-main, because the steam generated in a boiler makes room for itself by pressing on the surface of the water and forcing it back out of the boiler into the street-main. This relieves the boiler at the expense of the coolness and purity of the supply to other houses. It is easy to make thin-metal boilers resist this moderate expansive strain. The other strain—that due to a 45 sudden vacuum produced in a boiler—is more destructive. It causes a prompt collapse of thin metal of any ordinary thickness. It is

liable to occur under several conditions. One is after the boiler has become filled with steam which has forced out the whole or a large portion of the water. On the return of the water, whenever it occurs, cold water is presented to the steam, condensing all that remains. The strong vacuum thus induced collapses the boiler before the dense water can flow in through the small pipe from the street to fill it.

55 My ceramic boiler resists the compressive strain due to a perfect vacuum in its interior. Its strength against that class of strain is unquestionable.

60 I can make the entire boiler in one piece, except a cover of moderate area at one contracted end. The manufacture of ceramic ware and the proper glazing and baking requires a considerable orifice somewhere. I produce it 65 at the lower end and close it by a tight-fitting cover held by a strong bolt, with peculiar provisions for expansion and contraction, as also to allow a slight separation of the cover from the main body to relieve the excess of pressure 70 when steam is actively made.

75 Referring to the drawings, Fig. 1, and letters of reference thereon, A is the main body of my boiler; A', the upper end, smoothly rounded; A², a portion of the lower end, rounded in a 80 form closely approximating to that of the top; and a, a liberal opening in the center of the lower end, which is closed by a tight-fitting cover, B, which I will describe farther on.

85 A³ is a flange formed on the boiler, and by which it is supported in a suitable casting, C. A rod, M, of iron or steel, covered with tin, zinc, copper, or brass to avoid iron rust, extends axially through the boiler, having a broad head, M', at the top, nicely turned on its 90 under face, and a screw-thread at the bottom receiving a nut, N. It will be understood that the rod extends through a hole at the top. The joint is made tight by a soft washer, of rubber or other suitable material, fitted under 95 the head M'. The rod extends through a hole in the cover B, which is peculiarly formed and equipped. The upper portion of the hole is small. The lower portion, b, is enlarged and tapered. In the lower portion, b, is applied a 100 thick ring of vulcanized rubber, so proportioned as to extend nearly, but not quite, to the contracted top of the cavity. A stout spiral spring, G, abutting against the nut N, acts

on the rubber D through the medium of a thin plain washer, E, which may be of iron. The force urges the rubber D strongly upward and contracts it in the tapering cavity b. It compels it to form a tight joint against the tapering surfaces of the cavity b, and also inward against the surface of the bolt M.

The abutting faces of the parts A² and B are ground, so as to fit tightly together. I introduce a thin washer of rubber between these surfaces, to increase the certainty of a tight joint, cementing it permanently upon one of the surfaces of the parts—preferably that of the cover B. A turning of the nut N in one direction or the other adjusts the force with which the spring G is urged upward, and consequently with which the cover B is held up. The changes of temperature are liable to expand the axial bolt or rod M to a greater or less extent than the boiler A A' A² A³. The spring G must be sufficiently elastic to allow for such changes and maintain a practically uniform force.

When steam under any conditions causes an increase in the pressure in the boiler, so as to require a vent, the same means which is available for other boilers may be applied here, allowing the water to be forced outward or backward against the pressure in the street-main; but in case that cannot sufficiently relieve the boiler the excess of pressure is allowed to depress the cover B against the force of the spring G, and thus afford relief, in the manner of a safety-valve. So soon as the pressure in the boiler is sufficiently reduced the joint is again tightly stopped by the rise of the cover B, due to the tension of the spring G.

The junctions of the several pipes to the boiler may be of the ordinary number, and arranged in the ordinary manner, so as to circulate the water, as usual, freely through pipes leading from the boiler to the range (not represented) and back again, and also to allow the induction of the water from the street, and in especial emergencies the ejection thereof by the same route, and, of course, to allow the communication of the water from the interior of the boiler to the system traversing the house or building. I employ the usual internal boiler, (not shown,) receiving cold water from a tank (not shown) at the top of the house, at a higher pressure than obtains in the rest of the boiler, and returning it at a correspondingly higher pressure after it is heated by the presence of the surrounding hot water.

C is a casting adapted to properly support the boiler, receiving its flange A³, as shown.

By the employment of ceramic ware I avoid the fouling or contamination of the water experienced by the standing of the water in a heated condition in the ordinary metallic boilers. No oxide of iron, copper, or other metal is formed to injure the water for either culinary or laundry purposes. My boiler delivers it as pure as it comes in, simply raised in temperature.

Modifications may be made in the details. I can vary the length and diameter of the boil-

er, as also the thickness, the form of the ends, size of the hole a, which is stopped by the cover B, &c. The inside boiler and its connections may be dispensed with.

Some of the advantages of the invention may be realized without the spring G.

Fig. 2 represents a modification to which I attach especial importance. In this figure the ceramic-ware boiler is provided with a flange, which extends radially at its lower end, and is grasped by the metallic portion of the stand, as will be readily understood. The cover B, instead of being held elastically by a rod through the center of the boiler, is forced up to its seat by an adjustable screw. The joint between the cover and the main body may be formed by a rubber gasket, as in the other form, Fig. 1.

In the form shown in Fig. 1, I can arrange the spring at the top instead of at the bottom of the rod, and in such case can employ an ornamental casing over it to conceal it. I can put the cover B at the top instead of the bottom. This modification may offer some advantages by discharging steam instead of water in the rare event of the joint opening to serve as a safety-valve, and the joint will obviously be under less pressure by the difference in the head of water.

I propose to fit up the rod M with a screw-thread and a nut at each end, and to flatten the rod at one extremity, or at both extremities, to facilitate holding it while the nuts are adjusted.

Where my cover is not arranged to yield, I can employ an ordinary safety-valve loaded by a spring, or in any other convenient way, placed at the top, as a means of relief against other pressure.

I claim as my invention—

1. A boiler of rigid material having the orifice a stopped by a cover, B, in combination with each other and with the adjusting means N, and with provisions for tightly closing the orifice a, and for allowing for expansion and contraction, and for the relief action, as herein specified.

2. The cover B, having a tapering orifice, b, in combination with the elastic plug or contractile packing D, rod M, spring G, and boiler A, arranged to maintain a tight joint around the rod and allow a slight movement of the parts, as herein specified.

3. The range-boiler described, composed of ceramic material, having a large bottom orifice, a, in combination with the cover B, and means for holding the latter with adjustable force, and with the supporting-casting C, as herein specified.

In testimony whereof I have hereunto set my hand, at New York city, this 12th day of August, 1881, in the presence of two subscribing witnesses.

BERNARD MORAHAN.
